UNITED STATES PATENT OFFICE.

CLAYTON CHESTER FERGUSON, OF JERSEY CITY, NEW JERSEY.

SIGNAL DEVICE.

Application filed September 11, 1920. Serial No. 409,730.

To all whom it may concern:

Be it known that I, CLAYTON CHESTER FERGUSON, citizen of the United States, and resident of Jersey City, in the county of Hudson and State of New Jersey, have invented certain new and useful Improvements in a Signal Device, of which the following is a specification.

This invention relates to a signal device which is specially adapted to automobiles and various other vehicles. Its organization is characterized by a signal arm which can be swung and clamped in different positions. The arm has connected to its swinging end an electric bulb which is used at night, and adjacent thereto is located an elastic signal ball which also functions as a cushioning device when the arm is located in its horizontal or neutral position. The arm can be swung to different positions above the roof of the vehicle with which it is used, and to diametrically opposite positions. Shields are provided to hide both the bulb and ball when the arm is located in either of its horizontal positions. An electric switch connects with the bulb which breaks the electric circuit when the arm is located in either of its horizontal or neutral positions, and thereby current is only used when the arm with its bulb is swung to a position to signal.

Fig. 1 shows a fragmentary side view of a vehicle with the signal device in a lowered position; Fig. 2 shows a left hand side view of Fig. 1 with the signal indicated in its two elevated positions in dotted lines; Fig. 3 shows an enlarged top plan view of the signal with a partial axial section; Fig. 4 is an enlarged section of Fig. 3 on the line 4-4; Fig. 5 is a section of Fig. 3 on the line 5-5; Fig. 6 represents a section of Fig. 3 on the line 6-6; Fig. 7 shows an enlarged perspective view of the shield of the signal device; Fig. 8 is an elevation of a detail; Fig. 9 is an end view of a core of a switch; Fig. 10 represents an end view of a tubular cover; Fig. 11 shows an enlarged end view of an axle and Fig. 12 is an elevation of a tubular insulator.

In this instance the top or roof of an automobile is indicated in its entirety by the numeral 20 with the declining front portion 21, to which latter the signal device is attached. The device comprises the top

frame plate 25 which is located upon the declining front portion 21 of the top 20. A bottom clamping plate 26 is located below the portion 21, and the top frame plate 25, the portion 21 and the bottom clamping plate 26 are all connected together by means of bolts 27. The top frame plate 25 has formed therewith a journal housing 28 having the journal bearings 29 and 30. A tubular axle 32 is journaled in the bearings 29 and 30. The said axle has formed therewith the threaded ends 34 and 35 and a pair of flattened portions 33 with the slots 36.

An electric switch is designated in its entirety by the numeral 40 and comprises the core 41 of electric insulating material with the oppositely positioned flattened faces 42, 43. Slots 44 are formed in one end of the core 41. A tubular cylindrical metallic cover 45 with the flattened portions 46 and 47 covers the core 41 and has formed therewith the lips 47^a and 47^b. A filler 48 with the axial opening 48^a and the lugs 49 is located in the axle 32, the lugs 49 extending into and locking with the slots 44 of the core 41.

An electric insulating plug 50 with the annular openings 51 is supported on the axle 32, and the openings 51 engage the end 35 of said axle. An elbow 52 is connected to the threaded end 34 of the axle 32 and has in turn connected thereto the tubular signal arm 53. The latter at its outer end has formed therewith the threaded portion 54. A sleeve 55 with the socket end 56 is in threaded engagement with the threaded portion 54. An electric light bulb 57 is shown with its socket 58 that is in threaded engagement with the socket end 56 of the sleeve 55.

A wire 60 for electric current having the insulating cover 61 extends through the axle opening 48^a of the filler 48. One end of the wire 60 is bent over and in contact with the metallic cover 45 as indicated at 63. The end 63 is maintained in place against the lip 47^a of the metallic cover 45 by means of the plug 50. The wire extends through the axle 32, elbow 52, signal arm 53 and sleeve 55. The end of the wire 60 in the sleeve 55 has connected thereto the eyelet 64 with the flange 65 which latter bears against the central pole button 66 of the bulb 57. An elastic tubular insulator 67 encircles the

wire 60 in the sleeve 55 and bears between the adjacent end 68^a of the signal arm 53 and the flange 65 of the eyelet 64, to maintain electric contact between said eyelet and pole button 66 of the bulb 57. The tubular insulator 67 is preferably split on a helical line 68 so as to be easily located in place. A red elastic signal and cushioning ball 69 surrounds the signal arm 53 adjacent to the bulb 57. The ball also functions as a signal device in the day time.

A metallic washer 70 encircles the flattened portions 33 of the axle 32 and is located between one end face of the journal 15 housing 28 and the core 41. A nut 74 on the threaded end 35 of the axle 33 bears against the plug 50.

A block 75 of insulating material extends from the lower face of the clamping plate 26 and supports the spring switch blade 76. A binding post 77 on the block 75 has connected thereto the wire 78 which is connected to a source of electric current not shown. A second wire 79 extends from the clamping plate 25 26 for the electric circuit.

An operating handle 82 is supported on a shank 83, which has formed therewith a collar 84 and a pair of stop lugs 85 and 86. The collar 84 is fastened to the axle 33.

30 Shields 88 are fastened to the declining front portion 21 of the top 20.

To use the signal device the operator by means of the operating handle 82 swings the signal arm 53 in any position desired through an arc of 180 degrees. The arm may be frictionally maintained in any angular position if desired, by causing sufficient pressure between the washer 70 and the adjacent end of journal housing 28 and the other end of the 40 housing 28 and the elbow 52 by means of the nut 74.

When the operator desires to turn the car to the right or the left the arm 53 is swung to the positions indicated at R or L in Fig. 45 2. If the car is to stop the arm is swung to a vertical position. Should the operator desire to back the car the arm 53 may be vibrated.

In the day time the locations of the arm 53 are augmented by the ball 69 and at night by means of the electric bulb 57. The shields 88 hide both the ball 69 and bulb 57, when the arm is in a horizontal or neutral position.

The electric current that is supplied to the 55 bulb 57 flows from the wire 78 to the binding post 77 and thence through the switch blade 76. For the current to reach the bulb the operator by means of the handle 82 swings either curved portion of the wall of the cover 45 into contact with the switch 60 blade 76 and closes the electric circuit. When the signal arm 53 is in either horizontal position the switch blade 76 is not in contact with the cover 45 because either flattened portion 46 or 47 of the cover 45 is opposite

said blade and the electric circuit is broken. By this means electric current is only used when the bulb 57 is located in one of its signaling positions. Also when the arm 53 is in either of its horizontal positions the bulb 70 57 and ball 69 are behind and hidden from view by one of the shields 88.

Having described my invention what I desire to secure by Letters Patent and claim is:

1. In a signal device for a vehicle the combination of a journal housing extending through the roof of the vehicle, said housing having formed therewith a top frame plate bearing on the top side of said roof, a bottom clamping plate bearing on the lower face of said roof, means to connect together the top frame plate, the roof and the bottom clamping plate, a tubular axle journaled in said housing, a signal arm on the upper side of said roof extending from said axle, an operating handle connected to said axle below said roof, said signal arm adapted to be swung to different positions above said roof by said handle and means to maintain the signal arm in different positions.

2. In a signal device for a vehicle the combination of a journal housing extending through the roof of the vehicle and detachably fastened thereto, an axle journaled in said housing, a signal arm on the upper side of said roof extending from said axle, an operating handle connected to said axle below said roof, said signal arm adapted to be swung to different positions above said roof by said handle, signal indicating means for said arm and a shield extending up from said roof to hide the signal indicating means when the arm is located in a predetermined position.

3. In a signal device for a vehicle the combination of a journal housing extending through the roof of the vehicle and detachably fastened thereto, an axle journaled in said housing, a signal arm on the upper side of said roof extending from said axle, an operating handle connected to said axle below said roof, said signal arm adapted to be swung to different positions above said roof by said handle, signal indicating means for said arm, a shield extended up from said roof to hide the signal indicating means when located in a predetermined position and cushioning means connected to said arm supporting the swinging end thereof when located in said predetermined position.

4. In a signal device for a vehicle the combination of a journal housing extending through the roof of the vehicle and detachably fastened thereto, an axle journaled in said housing, a signal arm on the upper side of said roof extending from said axle, an operating handle connected to said axle below said roof, said signal arm adapted to be swung to different positions above said roof by said handle, stop lugs for said handle to

bear up against the lower face of said roof when the signal arm is located in different positions, signal indicating means for said arm, a cushioning and signal ball on said 5 arm adjacent to said signal indicating means and a pair of shields extending up from said roof to hide the signal indicating means

and said ball when the arm is located in pre-determined positions.

Signed at the borough of Manhattan, city 10 of New York in the county of New York and State of New York this 28th day of August A. D. 1920.

CLAYTON CHESTER FERGUSON.
